T. I. POTTER

LIFE PRESERVER

Filed May 26, 1922.

III-2

Inventor

T. IRVING POTTER

By

Attorney

Alfred B. Bond

UNITED STATES PATENT OFFICE.

THOMAS IRVING POTTER, OF EAST ORANGE, NEW JERSEY, ASSIGNOR TO FEDERATED ENGINEERS DEVELOPMENT CORPORATION, OF JERSEY CITY, NEW JERSEY, A CORPORATION OF DELAWARE.

LIFE PRESERVER.

Application filed May 26, 1922. Serial No. 563,915.

To all whom it may concern:

Be it known that I, THOMAS I. POTTER, a citizen of the United States, and a resident of East Orange, in the county of Essex and State of New Jersey, have invented a new and Improved Life Preserver.

The invention relates to improvements in life preservers, an object of the invention being to provide a device of this character so constructed that it will support the head of an unconscious person out of the water.

A further object is to provide a life preserver which is reversible, which may be quickly donned or removed, which will be efficient in use, simple in construction and inexpensive to manufacture.

With these and other objects in view, the invention consists in certain novel features of construction, combinations and arrangements of parts as will be more fully herein-after described and pointed out in the appended claims.

In the accompanying drawings,

Figure 1 is a perspective view illustrating the manner of use of my improved life preserver.

Figure 2 is a plan view of the life preserver.

Referring in detail to the drawings, I have shown a life preserver designated in its entirety by the reference numeral 1 which is in the form of a jacket and which is provided with novel means for supporting the head of an unconscious person in such a manner that his face will be kept out of the water. The invention in this particular instance does not reside broadly in the provision of means for so supporting the head of a person using the life preserver but re-

sides more specifically in the provision of means integral with the jacket for doing so, thus eliminating the use of attached or attachable collars which greatly increase the cost of manufacturing the life preservers.

My improved jacket which is reversible as above noted, preferably comprises a single piece of flexible material. Straps or other suitable securing devices 2 are attached to the opposite side edges of the jacket and are adapted to be tied together at the front thereof to secure the same in position. Suitable arm holes 3 are provided for the reception of the arms of a wearer. The intermediate portion of the upper end of the piece of material which forms

the jacket is extended upwardly as indicated at 4 to provide an integral collar portion substantially rigid with the body of the jacket. Reinforcing buoyant bodies 5 are provided in the front of the jacket adjacent the edges thereof and are also provided in the center of the collar portion, the last mentioned buoyant bodies being designated by the reference numeral 6 and extending well down into the back of the jacket to effect a substantially rigid connection between the body and the collar. The collar is highest at its intermediate portion to effectively support the head of a person lying on his back in the water and the collar diminishes gradually in height from its intermediate portion to the point where it joins the upper edge of the front of the jacket adjacent the side edges thereof. These sloping web portions 7 at each side of the buoyantly reinforced part of the collar serve to effectively prevent the head of an unconscious man from rolling sidewise until the face is submerged.

Due to the buoyancy at the front of the jacket, a person using the same is almost instantly thrown over on his back when he falls into the water with the jacket on. The reinforced portion of the collar successfully maintains the head of a wearer out of the water when he is conscious and the webbed portions 7 prevent the head from rolling sidewise a dangerous distance should the wearer lose consciousness. As seen most clearly in Figure 1 of the drawings, the collar portion or extension 4 when the jacket is worn assumes the shape of what might roughly be termed an inclined head supporting trough.

The lower edge of the jacket is preferably cut away as indicated at 8 in a curve corresponding to the curve of the upper edge of the collar. This cut-away portion provides more freedom of movement for the wearer in the jacket and incidentally results in the saving of material in manufacture. Any approved means of securing the buoyant bodies 5 and 6 within or to the jacket as the case may be, may be resorted to and any approved type of buoyant material may be used in this connection.

I have illustrated one of the preferred embodiments of the invention, but various slight changes and alterations might be made in the general form and arrangement

of the parts described without departing from the invention and hence, I do not wish to limit myself to the precise details set forth, but shall consider myself at liberty to 5 make such slight changes and alterations as fairly fall within the spirit and scope of the appended claims.

I claim:

1. A life preserver comprising a flexible 10 body portion buoyantly reinforced adjacent its side edges, an integral head supporting extension at the intermediate portion of the upper edge of said body portion, buoyant reinforcing material arranged to extend 15 from adjacent the top of said extension to the intermediate portion of said body at a point normally disposed well below wearer's shoulders whereby to effect a substantially rigid connection between the body portion 20 and the head supporting extension.

2. A life preserver comprising a flexible body portion buoyantly reinforced adjacent its side edges, an integral head supporting extension at the intermediate portion of the 25 upper edge of said body portion, buoyant reinforcing material arranged to extend from adjacent the top of said extension to the intermediate portion of said body at a point normally disposed well below wearer's 30 shoulders whereby to effect a substantially rigid connection between the body portion and the head supporting extension, said extension including tapered side web

portions adapted to co-operate with the reinforced central portion thereof to form a 35 head receiving trough when the preserver is assumed.

3. A life preserver including a body portion, relatively long vertically extending buoyant reinforcements adjacent the side 40 edges of said body portion, an integral head supporting extension intermediate the ends of the upper edge of said body portion, a relatively short vertically disposed buoyant reinforcement at the intermediate portion of 45 the body extending well into said head supporting extension.

4. A life preserver including a body portion buoyantly reinforced adjacent its side edges, a head supporting extension intermediate the ends of the upper edge of said body portion, and means buoyantly reinforcing the central portion of said extension and effecting a substantially rigid connection between said extension and said body portion. 55

5. A belt or jacket life preserver comprising a flexible body portion buoyantly reinforced adjacent its edges, a substantially rigid longitudinally arranged buoyant reinforcement at the intermediate portion of 60 said body portion, the upper end of said reinforcement extending well beyond the shoulder line of the jacket to support and prevent rearward swinging movement of a wearer's head.

THOMAS IRVING POTTER.
